UNITED STATES PATENT OFFICE

2,064,071

DUPLICATING MACHINE

Alfred Marchev, La Grange, Ill., assignor to Ditto,
Incorporated, Chicago, Ill., a corporation of
West Virginia

Application October 14, 1935, Serial No. 44,923

6 Claims. (Cl. 101—132)

This invention relates to duplicating machines and is particularly adaptable to machines for system work such for example as that shown in the application of John W. Hernlund, Alfred 5 Marchev, and Robert F. Morrison, Serial No. 713,590, filed March 1, 1934, for Duplicators.

Machines of the type disclosed in the above identified application are adapted to duplicate sales data, cost data, and other statistics on forms which may or may not be of the same size. 10 Quite often in this type of work a relatively small number of duplicate copies are made, but it is necessary to give only a part of the full information contained upon the master sheet to one department while another part of the information on the master sheet may be given to another department. In providing the information in this 15 form, the operator may have all of the information on the master sheet, and then in making copies it is desirable to block out that part of the information which is of no value or should not be furnished to the particular department for which the copies are being made.

The improvement contemplated in the present 20 application is one which facilitates the accomplishment of this blocking out process directly on the duplicating machine. In the application of copy work to machines of this character, the master sheet may be shortened so that only a portion 25 of the drum is covered by the short master sheet. Now in duplicating from this short portion full size copy sheets may be used which are somewhat longer than the master sheet applied to the gelatin band.

By means of the present invention, the operator 30 may readily apply a blank sheet to cover that portion of the drum which is not covered by the short master sheet and thus prevent anything on the gelatin band covering said portion from being transferred to the copy sheet.

The objects and features of the invention will 35 be more apparent from the following description reference being had to the accompanying drawings in which—

Fig. 1 is a side view partly in section showing 40 the invention as applied to a duplicating machine of this system rotary type;

Fig. 2 is a fragmentary view of a portion of the structure in Fig. 1 showing a changed position;

Fig. 3 is a plan view of that portion of a duplicating machine to which the present invention is applied;

Fig. 4 is a sectional view on the line 4—4 of 45 Fig. 3;

Fig. 5 is a sectional view on the line 5—5 of Fig. 3;

Fig. 6 is a sectional view on the line 6—6 of Fig. 3; and

Fig. 7 is a sectional view on the line 7—7 of Fig. 3.

Referring now in detail to the drawings, the invention is shown as applied to a rotary drum type duplicating machine hereinbefore referred to. In this machine, the numeral 10 refers to 10 the drum which is suitably mounted on a shaft 11 supported in side frame members 12 and 13. In accordance with the disclosure in the aforementioned application, the side frames 12 and 13 carry sheet metal guards 14 and 15, respectively, 15 which extend inwardly over the ends of the drum 10.

The mechanism for rotating the drum 10 has not been illustrated as any suitable drive mechanism may be utilized for this purpose.

The drum 10 is provided with a duplicating band 16 (see Fig. 5) which may be the usual gelatin band employed in machines of this character. Sheets are fed to the drum 10 through a paper chute indicated generally by the numeral 17. A paper feed table is shown at 18, and a vertical paper guide is shown at 19. Sheets are stripped from the drum by a stripping mechanism indicated generally by the numeral 20 (see Figs. 1 and 3). This stripping mechanism comprises a pair of stripping rolls 21 and 22 carried upon an auxiliary frame having side frame members 23 and 24 to which a pair of end brackets 25 and 26 are secured. A receiving tray is shown partly at 27, this tray being of the usual construction. A cross bar 28 carries a pair of paper guides 29 and 30 for guiding sheets of paper stripped from the drum by the rollers 21 and 22 over the tray 27. A stripper bar 31 is shown in Fig. 3, this stripper bar being, of course, substantially the same as that shown in the prior application above referred to.

The brackets 25 and 26 have upwardly projecting arms 32 and 33 to which a block-out sheet feeding device 34 is secured. This feeding device has a frame consisting of sides 35 and 36, a cover portion 37, and an end portion 38, these portions being preferably formed integral with each other by being stamped out of sheet metal. The side portions 35 and 36 have arms 39 and 40 projecting therefrom and pivoted to the upwardly projecting arms 32 and 33 of the end brackets 25 and 26. Small angle iron stops 41 and 42 are secured to the top ends of the members 32 and 33 to provide a resting place for the feeding device 50 55

34 when it is lifted into the position shown in full lines in Fig. 2.

The feeding device 34 has a shaft 43 journalled in the sides 35 and 36 thereof. The shaft 43 has fixed thereon exteriorly of the sides 35 and 36 a pair of arms 44 and 45 which arms at their free ends support a shaft 46 of a platen roller 47. Also fixed to the shaft 43 there is provided a spring pressed arm 48 (see Fig. 7) which arm at 10 its free end has a stud 49 to receive a spring 50. Spring 50 at its upper end fits over a stud 51 mounted in the cover 37 of the feeding device 34. The spring 50 is under compression so as to normally tend to rotate shaft 43 in a clockwise direction as shown in Fig. 7 which will press the platen roller 47 downwardly toward the drum 10. A stop plate 58 (see Fig. 6) is riveted to the end portion 38 of the housing 34 and has a portion 59 projecting beneath the bearing for shaft 46 in 15 the arm 44 so as to operate as a stop to limit the downward movement of arm 44 with respect to the housing.

The side portions 35 and 36 have slots 52 and 25 53 respectively for receiving the shaft 46 of the roller 47 so that this roller can be moved up and down within the housing of the feed device 34. A guide plate 54 is mounted within the feed device 34 and secured to the side portions 35 and 36 as for example by being welded thereto. The function 30 of this guide plate is, of course, to guide block-out sheets such as 55 to the platen roller 47. The guide plate 54 has a guard or finishing strip 56 applied thereto. This strip consists of a nickel plated thin sheet metal strip folded over into U- 35 shape and fastened down upon the plate 54 by suitable screw bolts indicated at 57 in Figs. 3, 4, and 5.

When the feeding device 34 is not in use, it is folded up into the position shown in full lines in 40 Fig. 2. When the device is to be used, however, it is brought down into the dotted line position shown in Fig. 2 where a pin 60 which is fixed to one side 35 thereof engages an upstanding block 61 upon a sliding latch member 62 which is 45 mounted upon the guard plate 15 of the main frame of the machine. The latch member 62 has a sliding movement on the guard plate 15 being slidably mounted thereon by means of a pair of screw bolts 63 and 64 which screw bolts have 50 collars 65 and 66 thereon slidable in a slot 67 provided in the guard plate 15. A nut 68 and a washer 69 secure the collar 66 in position, the washer 69 being adapted to ride upon the under surface of the guard plate 15. A similar washer 55 70 is provided on the screw bolt 63 to hold the collar 65 in place, but the bolt 63 extends upwardly into the block 61 in which it is screw threaded. The block 61 has a slot 71 therein which slot is adapted to receive the pin 60 when the latch device 62 is moved from the position shown in Fig. 50 2 to that shown in Fig. 1.

When the mechanism is in the position shown in Fig. 1, the block-out device 34 is moved down into operative position with respect to the drum. 65 However, it is not in position to cause contact of the platen roller 47 with the gelatin band 16 on the drum as this contact is controlled by a cam and roller mechanism consisting of a cam 72 fixed to the end of the drum 10, for example, by 70 suitable screws such as 73 and a roller 74 which roller is carried by an arm 75 fixed to the shaft 43 by a hub 75' (see Fig. 3 and Fig. 4). The cam 72 normally holds the platen roller 47 raised above the duplicating surface on the drum by 75 engagement with the roller 74. However, on that

portion of the drum which would be left uncovered by a short master sheet, the cam 72 is discontinued leaving an open space between ends 76 and 77 of the cam 72 as illustrated most clearly in Fig. 4. The end 77 of the cam 72 does not terminate as abruptly as the end 76 thereof, but is turned inwardly toward the axis of the drum so as to gradually lift the roller 74 as the drum is rotated to bring the end 77 beneath the roller 74.

The operation of the device is substantially as follows: Assuming that the operator has applied a short master sheet to the gelatin band 16 on the drum and that he desires to feed a block-out sheet 55 onto the gelatin band to cover that portion which would otherwise be exposed and engage copy sheets of greater length than the master sheet as the copy sheets are fed to the drum, the operator feeds the desired block-out sheet 55 onto the guide plate 54 into position to engage the platen roller 47. The platen roller 47 is made 20 of the usual rubber employed for this purpose. It is understood, of course, that in order to use the feeding device 34 the operator must bring it into the position shown in Fig. 1.

Now when the drum rotates, the roller 74 will drop off the end 76 of the cam 72 thus allowing the platen roller 47 to press the block-out sheet 55, which has been fed underneath it, down against the surface of the gelatin band and thus feed the block-out sheet onto the portion of the 30 gelatin band it is desired to cover. The cam 72 is so constructed and applied to the drum in order to release the block-out feeding device at the proper position. To fit different sizes of block-out requirements, the cam 72 may be modified 35 as desired so that it is possible to cover any particular portion of the gelatin band with the block-out sheet. When the block-out sheet is applied, copies are then made in the regular fashion with the block-out sheet left in place so as to prevent 40 the copy sheets from being printed with any material that might be on that part of the band beneath the block-out sheet.

Thus it is possible to use the short master sheets in such a fashion as to substantially cover 45 all of the band without the necessity of leaving wide unused spaces on the band and without any danger of picking up upon the copy sheet any imprints from that part of the band not covered by the short master sheet.

While one embodiment of the invention has been shown and described, it is to be understood that it is capable of many modifications. Changes, therefore, in the construction and arrangement may be made without departing from 55 the spirit and scope of the invention as disclosed in the appended claims in which it is the intention to claim all novelty inherent in the invention as broadly as possible in view of the prior art.

The invention having thus been described, 60 what is claimed as new and desired to be secured by Letters Patent is:

1. A duplicating machine comprising a frame, an impression drum journalled therein, a duplicating band on said drum, a copy sheet guide to 65 direct sheets to said drum, stripping means to remove sheets from said drum, and an auxiliary sheet feed device having means to supply a block-out sheet to a portion of the duplicating band on said drum said device including means to press 70 the block-out sheet into intimate contact with said band as the block-out sheet is supplied.

2. A duplicating machine comprising a frame, an impression drum journalled therein, a duplicating band on said drum, a copy sheet guide to 75

- direct sheets to said drum, stripping means to remove sheets from said drum, and an auxiliary sheet feed device having means to supply a block-out sheet to a portion of the duplicating band on 5 said drum, said auxiliary device comprising a frame movable toward and away from said drum, a platen roller carried by said last named frame, and a sheet guide for directing sheets between the drum and said roller.
- 10 3. A duplicating machine comprising a frame, an impression drum journalled therein, a duplicating band on said drum, a copy sheet guide to direct sheets to said drum, stripping means to remove sheets from said drum, and an auxiliary 15 sheet feed device having means to supply a block-out sheet to a portion of the duplicating band on said drum, said auxiliary device comprising a second frame pivoted on the machine and a platen roller in said second frame.
- 20 4. A duplicating machine comprising a frame, an impression drum journalled therein, a duplicating band on said drum, a copy sheet guide to direct sheets to said drum, stripping means to remove sheets from said drum, and an auxiliary 25 sheet feed device having means to supply a block-out sheet to a portion of the duplicating band on said drum, said auxiliary device comprising a second frame pivoted on the machine and a platen roller in said second frame, a shaft for 30 said roller, shaft supporting means movable with respect to said second frame, spring means pressing said shaft supporting means in one direction, means on the drum opposing movement of said supporting means by said spring during a portion of the rotation of the drum.
5. A duplicating machine comprising a frame, an impression drum journalled therein, a duplicating band on said drum, a copy sheet guide to direct sheets to said drum, stripping means to remove sheets from said drum, and an auxiliary sheet feed device having means to supply a block-out sheet to a portion of the duplicating band on said drum, said auxiliary device comprising a second frame pivoted on the machine and a platen roller in said second frame, a shaft for said roller, shaft supporting means movable with respect to said second frame, spring means pressing said shaft supporting means in one direction, means on the drum opposing movement of said supporting means by said spring during a portion of the rotation of the drum, and stop means on said second frame limiting movement of said supporting means by said spring.

ALFRED MARCHEV.
